UNITED STATES PATENT OFFICE

168,574

GAME BOARD

Steve Kerro, Indianapolis, Ind.

Application September 2, 1952, Serial No. 21,283

Term of patent 7 years

(Cl. D34—5)

To all whom it may concern:

Be it known that I, Steve Kerro, a citizen of the United States, residing at Indianapolis, State of Indiana, have invented a new, original, and ornamental Design for a Game Board, of which the following is a specification, reference being had to the accompanying drawing, forming a part hereof.

The single figure of the drawing is a top plan view of a game board, showing my new design.

The game board is of conventional thickness.
I claim:

The ornamental design for a game board, as shown and described.

STEVE KERRO.
